COMBINATION BAGGAGE RACK AND
LIGHTING FIXTURE

Carl H. Larson, Elkhart, Ind., John L. Mohun,
Chicago, Ill., and Christian M. Verhagen, Elkhart, Ind., assignors to The Adlake Company, Elkhart, Ind., a corporation of Illinois

Original application April 13, 1936, Serial No. 74,004. Divided and this application July 26, 1937, Serial No. 155,806

9 Claims. (Cl. 240—7.1)

This application is a division of our application filed April 13, 1936, Serial No. 74,004, which has matured into Patent #2,091,599.

This invention relates to baggage racks for railway cars, buses, and the like, and some of the more important objects of the invention are as follows: To provide a rack which is made up of readily assembled units; to combine a lighting fixture with the rack in such a manner that not only is proper lighting effected, but the appearance of the rack as a whole is greatly improved; to provide means for obtaining access to the lighting fixture without completely disassembling the rack; and to construct the wall bracket and rack unit in such a way that slight variances in the positioning of the bracket are accommodated without being apparent to persons within the car.

Further and other objects and advantages will become apparent as the disclosure proceeds and 20 the description is read in conjunction with the accompanying drawings, in which

Fig. 1 is a perspective view showing a preferred embodiment of the invention;

Fig. 2 is a vertical, transverse, sectional view 25 taken on the line 2—2 of Fig. 4;

Fig. 3 is a longitudinal, horizontal, sectional view taken on the line 3—3 of Fig. 4;

Fig. 4 is a longitudinal, vertical, sectional view 30 taken on the line 4—4 of Fig. 3;

Fig. 5 is a perspective view of the wall bracket with the cover lifted and parts broken away to expose the interior of the bracket;

Fig. 6 is a perspective view of the rack unit; and

Fig. 7 is a perspective view of the end bracket 35 for the baggage rack.

It will be understood that the choice of a particular embodiment of the invention for illustration and description is for the purpose of complying with Sec. 4888 of the revised statutes with respect to disclosure, but the appended claims are not to be limited to the construction shown and described unless the prior art requires that interpretation.

Referring first to Fig. 1, it will be seen that the 45 rack consists of a plurality of rack units 10 (see also Fig. 6), end pieces 11 (see also Fig. 7), and a plurality of intermediate wall brackets, generally designated 12, the latter serving the double function of supporting the rack units 10 and containing lighting fixtures for illuminating the car interior.

The rack units 10 (Fig. 6) comprise a plurality of parallel supports 13, in the present case tubes, the ends of which are rigidly secured to right and 55 left section castings 14 and 15, respectively, which

may be called the baggage-supporting element end pieces. The two castings are similar, and each is provided with a plurality of openings 16 into which the tubes are fitted and held in place by flaring over the ends of the tubes, as shown at 17 5 in Fig. 3. The castings are provided with a small outwardly extending flange 18 along their bottom, forward and top margins, the flange along the top margin, however, being slightly wider and provided with ears 19 adapted to overlap the wall 10 brackets 12 to enable the unit to be secured to the bracket. Elongated slots 20 in the ears 19 accommodate slight variances in the positioning of the wall bracket, as will be later described in more detail. 15

The section castings 14 and 15, as well as the tubes, are preferably made of aluminum, although other material may, of course, be used.

The end piece 11 (Fig. 7) consists of an aluminum casting which, in general, has a shape corresponding to the section castings 14 and 15. Assuming that the end piece is for the right end of the rack (as shown in Figs. 2 and 7), it will be seen that the section casting 14 is adapted to interfit with the end piece, with the top and bottom portions of the marginal flange 18 resting upon the top and bottom flanges 21 and 22, respectively, of the end piece, and small cap screws 23 passing through the elongated slots 20 in the section casting 14, and tapped holes 24 in the 30 flange 21 secure the rack unit in place on the end piece. 25

It will be noticed in Fig. 2 that there is a clearance 25 between the section casting 14 and the end piece 11, which enables slight variances in the 35 positioning of the end piece 11 to be accommodated, and at the same time the bottom flange 22 of the end piece masks the spacing of the rack unit 10 from the end piece.

The end piece is secured to the car wall by suitable fastening means, as, for example, machine screws 26. 40

The wall brackets 12 each comprise a box housing 27, which extends substantially the full width of the rack, the top of the housing being 45 closed by a cover 28 and the bottom by a light-transmitting wall or bowl 29. The housing is preferably cast in aluminum, and has outwardly extending side ledges 30, upon which the flanges 18 of the adjacent rack units 10, or the downwardly facing surfaces thereof, are adapted to rest (see Fig. 2). The upper enlarged portion of each end piece 14, 15, or the downwardly facing surface thereof, is adapted to rest upon the top wall of the housing, which constitutes a sup- 50 55

porting ledge with the ears 19 mating with lugs 31 formed on the housing, or on a transverse member thereof connecting the side walls of the housing. The lugs have tapped holes 32 for receiving cap screws 33, which also pass through the elongated slots 20 in the ears 19 to hold the rack unit 10 in adjusted position on the wall bracket. As in the case of the end piece 11, the ledges 30 on the wall brackets 12 mask the spacing of the rack units 10 from the bracket so that, viewed from below, the rack has a neat appearance.

Within the housing 27 are lamp units 34, 35 and 36, the first two being used for ordinary lighting and controlled by a switch 31, and the smaller unit 36 being used as a night light under the control of the car attendant from a remote point. The lamp units 34 and 35 are supported in the housing by angle brackets 38 and 39, respectively, which are secured to one of the side walls of the housing by small nuts and bolts 40. Preferably the lamp units 34 and 35 are slightly out of axial alignment so as to provide suitable clearance for the lamp unit 36 and allow the bulbs of any one to be removed without interference from either of the other bulbs within the housing.

The bowl 29 is removably secured in the housing, and comprises a molded translucent glass dish having slightly flared side walls 41 and end lips 42, the forward one of which is adapted to rest on the floor of the housing 27 (see Fig. 4), preferably a small gasket 43 is interposed between the lip and the housing, and the other upon a retaining strip 44 which is removably secured to the housing by small screws 45 entering lugs 46 formed on the floor of the housing 27.

In other words, the bowl is assembled with the housing by first inserting the forward edge 40 through the opening in the lower wall of the bracket and allowing the forward lip to rest on the floor of the housing, and then the rear portion of the bowl is raised into position and held in place by the retaining strip 44. In order to insure that the bowl 29 will not rattle within the bracket, rubber strips 47 are secured to the inner side walls of the housing by retaining clips 48, held in place by nuts and bolts 49 (Fig. 2), and when the rear end of the bowl is lifted into place for application of the retaining strip 44 the side walls 41 of the bowl make firm engagement with the rubber strips 47 and prevent movement of the bowl relative to the bracket.

A plurality of binding posts 50 are fastened 55 to the rear wall of the housing 27, and a pair of openings 51 on each side of the housing and in axial alignment with the two rear tubes of the rack units (see Figs. 3, 5 and 6) enable the necessary wiring to pass through the rack units 60 obscured from the sight of passengers.

Access to the interior of the bracket is obtained through the cover 28, which is hinged to the housing 27, as indicated at 52, and overlaps the top flange of the adjacent section castings 65 (see Fig. 2). The cover is provided with a closed rubber gasket 53, which, when the cover is secured in place by the thumb screw 54, positively insures that no light will leak out through the housing to cause undesirable lights and 70 shadows.

To increase the effectiveness of the lighting the cover 28 is equipped with a pair of reflectors 55, suitably spaced from the cover by brackets 56, as best shown in Fig. 4.

From the above description it will be seen that

access to the lighting unit may be obtained by merely unscrewing the thumb screw 54 and opening the cover, and that in case the wall bracket must be removed for repair of the fixtures the removal may easily be effected by 5 merely taking off the adjacent rack units and then unscrewing the screws 57 which hold the bracket to the wall.

We claim:

1. In a vehicle, the combination of spaced wall 10 brackets adapted to be secured to a side wall of the vehicle, a baggage rack unit, means for removably supporting the unit on the brackets, each of said brackets being in the form of a box housing, extending throughout substantially 15 the entire width of the rack unit and being of relatively deep cross section and supported from the wall at vertically spaced points to make the brackets cantilevers of sufficient strength to carry the baggage rack load, a source of light 20 within each bracket, the major portion of the bottom wall of the housing being light transmitting.

2. In a vehicle, the combination of spaced wall 25 brackets adapted to be secured to a side wall 25 of the vehicle, a baggage rack unit, means for removably supporting the unit on the brackets, each of said brackets extending substantially the 30 entire width of the rack unit and including a box housing of relatively deep cross section, the 35 brackets being supported on the side wall at vertically spaced points to make the brackets cantilevers having sufficient strength in conjunction with the deep cross section of the box housing to carry the major portion of the baggage rack 40 load, a main source of light within each bracket, an auxiliary source of light within each bracket, the major portion of the bottom wall for the housing being light transmitting, and a switch associated with the bracket for controlling the main source of light.

3. In a vehicle, the combination of spaced wall 45 brackets adapted to be secured to a side wall of the vehicle, a baggage rack unit, means for removably supporting the unit on the brackets, each of said brackets including a box housing of relatively deep cross section and supported from the wall at vertically spaced points to make the bracket a cantilever of sufficient strength to carry the baggage rack load, a source of light 50 within each box housing, the major portion of the bottom wall of the housing being light transmitting.

4. In a vehicle, the combination of spaced wall 55 brackets adapted to be secured to a side wall of the vehicle, a baggage rack unit, means for removably supporting the unit on the brackets, each of said brackets extending substantially the 60 entire width of the rack unit and including a box housing of relatively deep cross section, the brackets being supported on the side wall at vertically spaced points to make the brackets cantilevers having sufficient strength in conjunction with the deep cross section of the box housing to carry the major portion of the baggage rack load, 65 at least a portion of the bottom wall of the housing being light transmitting.

5. In a vehicle, the combination of spaced wall brackets adapted to be secured to a side wall 70 of the vehicle, a baggage rack unit, means for removably supporting the unit on the brackets, each of said brackets extending substantially the 75 entire width of the rack unit and including a box housing having spaced substantially straight vertical walls of relatively deep cross section, a bot-

- tom wall, and a top wall, the brackets being supported on the side wall at vertically spaced points to make the brackets cantilevers having sufficient strength in conjunction with the deep side walls 5 of the box housing to carry the major portion of the baggage rack load, at least a portion of the bottom wall of the housing being light transmitting.
6. In a vehicle, the combination of spaced wall 10 brackets adapted to be secured to a side wall of the vehicle, a baggage rack unit, means for removably supporting the unit on the brackets, each of said brackets extending substantially the entire width of the rack unit and including a box 15 housing having spaced substantially straight vertical walls of relatively deep cross section, a bottom wall and a top wall, the brackets being supported on the side wall at vertically spaced points to make the brackets cantilevers having sufficient 20 strength in conjunction with the deep side walls of the box housing to carry the major portion of the baggage rack load, at least a portion of the bottom wall of the housing being light transmitting, the upper wall of said housing being removable 25 to provide access into the housing.
7. In a vehicle, the combination of spaced wall brackets adapted to be secured to a side wall of the vehicle, a baggage rack unit, means for removably supporting the unit on the brackets, 30 each of said brackets extending substantially the entire width of the rack unit and including a box housing having spaced substantially straight vertical walls of relatively deep cross section, a bottom wall, and a top wall, the brackets being supported on the side wall at vertically spaced points to make the brackets cantilevers having sufficient 35 strength in conjunction with the deep side walls of the box housing to carry the major portion of the baggage rack load, at least a portion of the bottom wall of the housing being light transmitting, a source of light in the housing, the top wall 40
- of the housing being removable to provide access into the housing, and a reflector behind the light source directing light downwardly through the light transmitting portion of the lower wall and being secured to the removable top wall. 5
8. In a vehicle, the combination of spaced wall brackets adapted to be secured to a side wall of the vehicle, a baggage rack unit, means for removably supporting the unit on the brackets, each of said brackets extending substantially the 10 entire width of the rack unit and including a box housing having spaced substantially straight vertical walls of relatively deep cross section, a bottom wall and a top wall, the brackets being supported on the side wall at vertically spaced 15 points to make the brackets cantilevers having sufficient strength in conjunction with the deep side walls of the box housing to carry the major portion of the baggage rack load, at least a portion of the bottom wall of the housing being 20 light transmitting, one of the walls of the box housing being removable to provide access into the housing.
9. In a vehicle, the combination of spaced wall brackets adapted to be secured to the side 25 wall of the vehicle, a baggage rack unit, means for supporting the unit on the brackets, each of said brackets extending substantially the entire width of the rack unit and including a box housing of relatively deep cross section, the brackets 30 being supported on the side wall at vertically spaced points to make the brackets cantilevers having sufficient strength in conjunction with the deep cross section of the box housing to carry the major portion of the baggage rack load, at 35 least a portion of the bottom wall of the housing being light transmitting.
